UNITED STATES PATENT OFFICE

ALFRED PERL, OF VIENNA, AUSTRIA, ASSIGNOR OF ONE-HALF TO OSCAR KOHORN & CO., OF CHEMNITZ, GERMANY

MACHINE FOR THE WET TREATMENT OF TEXTILE MATERIAL

Continuation of application Serial No. 210,409, filed August 3, 1927, and in Germany July 20, 1926.
This application filed January 28, 1930. Serial No. 424,119.

My invention refers to the wet treatment of textile material, and more especially to the wet treatment of ropes of textile threads, for instance, filaments of artificial silk.

5 It is an object of my invention to provide means whereby the material is treated with various chemicals or solutions in liquid condition and in a single operation and at a minimum of power expenditure, without the 10 threads in the ropes becoming entangled, and in such manner that the chemicals or solutions are distributed uniformly throughout the ropes.

To this end I provide a rod on which the 15 rope is suspended, a set of pairs of rollers adapted to support and to rotate the rod, and a system of rocking levers moved in unison for shifting the rod from one pair of rollers to the next pair.

20 In the drawings affixed to this specification and forming part thereof a machine embodying my invention is illustrated diagrammatically by way of example.

In the drawings

25 Fig. 1 is an elevation of the machine, with parts broken away,

Fig. 2 is an end elevation of the machine, partly in section on the line II—II in Fig. 1, and

30 Fig. 3 shows details of the machine on a larger scale.

Referring to the drawings, the machine frame has two parallel uprights A and B. It may be of any desired length and only 35 one of its ends is illustrated in Fig. 1. 1 are the rods referred to, on which the ropes C are suspended. The rods are preferably provided with a lining 1' of hard rubber or the like and bear cylindrical flanges 2 at or 40 near their ends, which may be integral with the rods or may be replaced by rings which are secured on the rods.

45 Fig. 2, and 3, 3', 4, 4', etc., are pairs of

rollers the shafts of which are rotatably supported in the brackets 39 at one end, and in one of the uprights A, B at the other, and are adapted to support the flanges or rings 2 of the rods 1. Rotation is imparted to 50 the rollers from two shafts 37 which extend in parallel relation with the outer faces of the uprights A, B, and are driven from a pulley 24 on a shaft 29 which is supported in suitable bearings of a subsidiary frame 55 D, and may be provided with a fly-wheel 25. 40 is a sprocket on the shaft 29 from which a chain 42 extends to a sprocket 41 on one of the shafts 37. The other shaft 37 is rotated by similar means, also from the shaft 29. 26 are helical gears on the shafts 37 and 36 are corresponding gears on the shafts of the rollers 3 . . . . Rotation in opposite directions is imparted to the rollers of one pair with respect to those of the next pair, 60 in such manner, that, as indicated by the arrows in Fig. 1, the rollers having odd numbers, as 3, 3', 5, 5', 7, 7' rotate in one direction, for instance, clockwise, and the rollers having even numbers as 4, 4', 6, 6', rotate 65 anti-clockwise, but the two rollers of a pair rotate in the same direction.

The rings or flanges 2 of the rods 1 are shifted from the rollers of one pair to those of the other pair, as will be described, and 70 thereby are rotated in opposite directions. Intermediate each pair of rollers, bearings 38 are provided on the brackets 39 which support the rods 1 and hold their rings or flanges 2 out of contact with the last roller of a preceding pair and the first roller of the following pair, as these rollers rotate in opposite directions.

8, 8' etc. are troughs arranged above the rods 1 and supported by suitable brackets 8''. 85 Liquid for desulfurizing, bleaching, soaping and any other treatment of the rope C, is contained in the troughs which are perforated at 9, Fig. 2, so that the liquid trickles down through the perforations and onto the ropes. 90

The means for shifting the rods 1 are supported on vertically reciprocating rails 10, one at either side of the machine. 11, 11 are rocking levers, one for each pair of rollers, 3, 3' . . . which are fulcrumed at 13 in bearings 27 on the rails 10 and at their upper ends are provided with bearings 14 for engaging the ends of the rods 1 which project beyond the intermediate bearings 38, as best seen in Fig. 2.

10 Reciprocation is imparted to the rails 10 by eccentrics 12 the straps 12' of which are secured to the lower face of each rail 10. 19 are the shafts of the eccentrics which are supported in suitable pairs of uprights E, E at the outer side of the frames A and B. Rotation is imparted to the shafts 19 through the medium of shafts 30 which are supported in bearings of uprights F, F, helical gears 18 on the shafts 30, and helical gears 43 on the eccentric shafts 19. 17 is a spur gear at the end of the shaft 30, and 17' is a pinion on an extension 29' of the driving shaft 29 which meshes with the gear 17. 16 is a friction clutch by which the extension 29' is connected with the shaft 29, 31 is a spring on the shaft 29 which tends to connect the parts of the friction clutch, 22 is a clutching lever which is fulcrumed on the frame D, one end of the lever engaging a sleeve 16' on the part of the clutch which is mounted to slide on the shaft 29, 21 is a roller at the free end of the lever, 20 is a disc which is circular and notched for the reception of the roller 21, 23' is a helical gear on the shaft of the disc 20, and 23 is a helical gear on the driving shaft 29 which meshes with the gear 23' so that continuous rotation is imparted to the disc 20.

40 While the roller 21 is in contact with the concentric portion of the disc 20, the lever 22 is held in a position in which it throws out the clutch 16 and compresses the spring 31, but when the roller 21 enters the notch in the disc 20 under the reaction of the spring 31, as shown in Fig. 1, the spring 31 is free to throw in the clutch 16 so that rotation is imparted to the shaft 30 and to the eccentrics 12. Obviously, the means for rotating the shafts 30 are duplicated at either side of the machine as the shafts 19 do not extend across the frame uprights A and B. The notch in the disc 20 is so large that the eccentrics 12 perform a complete revolution while the clutch 16 is thrown in.

60 The rails 10 and the points 13 at which the levers 11 are fulcrumed, describe a complete circle for each revolution of the eccentrics 12. 28 are open eyes at the lower ends of the levers 11, and 15 are pins on parallel bars G which extend in parallel relation with the uprights A and B and may be connected to the inner uprights E, E. In this manner the lower ends of the levers are retained by the eyes 28 while the points 13 about which they rock,

move on a circle with the rails 10. The forks 14 at the ends of the levers 11 also move along circles the diameter of which, however, is greater than that of the circles described by the rails 10. Each fork 14 engages one of the rods 1, lifts it from the pair of rollers with which it is in operative connection at the time, for instance the rollers 3 and 3', and places it on the intermediate bearings 38. Upon the next revolution of the rails 10, the 75 rod is removed from the intermediate bearing 38, and shifted to the following pair of rollers 4, 4', etc. and, as all levers 11 are operated at the same time, the shifting of all rods 1 occurs simultaneously throughout the machine.

15 The rails 10 are operated intermittently by the mechanism connected with the continuously rotating disc 20. In this manner, each rod is removed from one pair of rollers, deposited on one of the intermediate bearings 38, and from this bearing is transferred to the next pair of rollers, as often as the rails 10 are reciprocated.

20 Experience has shown that the operation 90 of the levers 11 is performed without difficulty, as the weighted rods 1 after their forks 14 have been raised beyond the upper limit of their stroke, exert sufficient power for depressing the levers 11, the rail 10 and the parts connected therewith, so that the bearings 14 move away from the rods 1 and release the rods for rotation by anyone of the pairs of rollers.

25 The number of troughs 8 is determined in 100 accordance with the character of the material to be treated. Intermediate each two troughs, the troughs 8 and 8' as shown in Fig. 1, the trough 8' and the trough next succeeding it, not shown, etc., there is an interval 105 in which the rods are not supplied with liquid and are not rotated, so that the liquid is permitted to flow from the ropes and collected in a suitable reservoir, not shown. The interval extends from the last roller of one 110 trough to the first roller of the succeeding trough, in the present instance from the roller 7 to the roller 33. Intermediate bearings 44 like the bearings 38, are formed on the brackets 39, the first bearing being at the rear 115 of the roller 7', and the last bearing being in front of the roller 33. 32 is a bracket on each rail 10 which cooperates with each set of intermediate bearings 44 and is provided with depressions 35 at the top. A rod which has 120 left the last roller 7' of the first trickling zone below the trough 8 is raised by the corresponding rocking lever 11, and shifted to the first intermediate bearing 44. Upon the next reciprocation of the rails 10, the rod is engaged by the first depression 35 and shifted to the next intermediate bearing 44, and so on, until it has arrived at the last intermediate bearing in front of the roller 33 where it is 125 engaged by the first rocking lever 11 of the set 130

30

of rocking levers which is allotted to the trough 8' and shifted to the pair of rollers 33, 33, of the second trickling zone.

Obviously the several rods must be pitched apart for such a distance that the rope of a rod which is being rotated will not be interfered with by the succeeding rod. In the diagrammatic drawings, Fig. 1, it has been assumed that there is a rod on each pair of rollers and on each intermediate bearing 38 and 44 but this is true only for the interval between two troughs where the rods are not rotated and therefore can be pitched quite closely. In this manner, the overall length 15 of the machine is much reduced by the shortness of the intervals and besides, access of air to the ropes intermediate two trickling zones is reduced to the minimum.

I wish it to be understood that I do not desire to be limited to the exact details of construction shown and described for obvious modifications will occur to a person skilled in the art.

In the claims affixed to this specification no 25 selection of any particular modification of the invention is intended to the exclusion of other modifications thereof and the right to subsequently make claim to any modification not covered by these claims is expressly reserved.

30 I claim:—

1. A machine for the wet treatment of ropes of textile materials comprising a rod on which a rope is suspended, a set of pairs of rollers adapted to support said rod, means for imparting rotation to said rollers, a system of rocking levers adapted to engage said rod and to shift it from one pair of rollers to the next pair, and means for rocking said levers.

2. A machine for the wet treatment of 40 ropes of textile materials comprising a rod on which a rope is suspended, a set of pairs of rollers adapted to support said rod, means for imparting rotation to said rollers, a system of rocking levers each having a bearing adapted to engage said rod and to shift it from one pair of rollers to the next pair, and means for rocking said levers.

3. A machine for the wet treatment of 50 ropes of textile materials comprising a rod on which a rope is suspended, a set of pairs of rollers adapted to support said rod, means for imparting rotation to said rollers, a pair of rails, means for imparting intermittent reciprocation to said rails, a system of rocking levers on said rails adapted to engage said rod and to shift it from one pair of rollers to the next pair, and means for rocking said levers.

4. A machine for the wet treatment of 60 ropes of textile materials comprising a rod on which a rope is suspended, a set of pairs of rollers adapted to support said rod, means for imparting rotation to said rollers, a pair of rails, means for imparting intermittent movement along a circle to said rail, a system of rocking levers on said rails adapted

to engage said rod and to shift it from one pair of rollers to the next pair, and means for rocking said levers.

5. A machine for the wet treatment of 70 ropes of textile materials comprising a rod on which a rope is suspended, a set of pairs of rollers adapted to support said rod, means for imparting rotation to said rollers, a pair of rails, means including an eccentric for imparting intermittent reciprocation to said rails, a system of rocking levers on said rails adapted to engage said rod and to shift it from one pair of rollers to the next pair, and means for rocking said levers.

6. A machine for the wet treatment of 75 ropes of textile materials comprising a rod on which a rope is suspended, a set of pairs of rollers adapted to support said rod, means for imparting rotation to said rollers, a pair of rails, means including a clutch for imparting reciprocating movement to said rails, means for alternately throwing in and out said clutch, a system of rocking levers on said rails adapted to 80 engage said rod and to shift it from one pair of rollers to the next pair, and means for rocking said levers.

7. A machine for the wet treatment of 85 ropes of textile materials comprising a rod on which a rope is suspended, a set of pairs of rollers adapted to support said rod, means for imparting rotation to said rollers, a pair of rails, a shaft, a clutch on said shaft operatively connected with said rails 90 so as to impart reciprocating movement thereto, a cam operatively connected with said shaft so as to be continuously rotated thereby, means operatively connected with said cam for alternately throwing in and out 95 said clutch, a system of rocking levers on said rails adapted to engage said rod and to shift it from one pair of rollers to the next pair, and means for rocking said levers.

8. A machine for the wet treatment of 100 ropes of textile materials comprising a plurality of troughs arranged at intervals, each trough constituting a trickling zone, a rod on which a rope is suspended, a set of pairs of rollers for each zone, said rollers being adapted to support said rod, means for imparting rotation to said rollers, a pair of rails, means for imparting intermittent reciprocation to said rails, a set of rocking 105 levers for each zone on said rails adapted to engage said rod and to shift it from one pair of rollers to the next pair, means for rocking said levers, and means on said rails 110 for moving said rod through the interval of two zones.

9. A machine for the wet treatment of 115 ropes of textile materials comprising a plurality of troughs arranged at intervals, each trough constituting a trickling zone, a rod 120

- on which a rope is suspended, a set of pairs of rollers for each zone, said rollers being adapted to support said rod, means for imparting rotation to said rollers, a pair of rails, means for imparting intermittent reciprocation to said rails, a set of rocking levers for each zone on said rails adapted to engage said rod and to shift it from one pair of rollers to the next pair, means for 5 rocking said levers, and means on said rails for moving said rod through the interval of two zones, said last mentioned means having depressions for engaging said rod which are pitched apart for a distance which is less than the pitch of the central intermediate lines of two pairs of said rollers.
10. A machine for the wet treatment of ropes of textile materials comprising a rod on which a rope is suspended, a set of pairs of rollers adapted to support said rod, means for imparting rotation to both rollers of each pair in the same direction, but in opposite direction to the rollers of two adjoining pairs, an intermediate bearing adapted 20 to support said rod between the last roller of each pair and the first roller of the succeeding pair, said bearing being so arranged as to hold said rod out of operative contact with said rollers, a system of rocking levers 25 adapted to engage said rod and to shift it from one pair of rollers to said intermediate bearing and to the next pair, and means for rocking said levers.
11. A machine for the wet treatment of ropes of textile materials comprising a frame, sets of pairs of rollers arranged at either side of said frame, intermediate bearings arranged between said pairs of rollers, a rail at either side of said machine, means for imparting intermittent reciprocating movement to 30 said rails, a set of rocking levers on each rail, means for imparting rocking movement to said levers through the medium of the reciprocating movement of said rails, a rod adapted to be supported at either end on the rollers of said pairs and on said intermediate bearings, said rod being adapted to support a rope, and means on said rocking levers for engaging said rod and for shifting it from 40 each pair of rollers to the adjacent intermediate bearing, and on to the next pair of rollers in time with the reciprocation of said rail.
12. A machine for treating ropes of textile threads with liquid comprising rods, rollers arranged in series below said rods, double-armed levers associated with said rollers and arranged to grip said rods and means for 50 simultaneously raising all said levers.
13. A machine for treating ropes of textile threads with liquid comprising rods, rollers arranged in series below said rods, double-armed levers associated with said rollers and 60 arranged to grip said rods and means for simultaneously raising and rocking all said levers.
14. A machine for treating ropes of textile threads with liquid comprising sprinkling troughs arranged in series in spaced relation, rods below said troughs, means below said troughs for rotating and means for lifting and shifting said rods in parallel to each other, a rake-shaped lifting device intermediate and below said troughs and means for 70 imparting to said device a circular movement.
- In testimony whereof I affix my signature.
